Primary Examiner — Sandra Snapp

(57) **CLAIM**

We claim the ornamental design for furniture, as shown and described.

DESCRIPTION

FIG. 1 is a front perspective view of furniture, according to one embodiment;

FIG. 2 is a front view of the furniture of FIG. 1;

FIG. 3 is a rear view of the furniture of FIG. 1;

FIG. 4 is a right side view of the furniture of FIG. 1, the left side view is a mirror image of the right side view of FIG. 4;

FIG. 5 is a top view of the furniture of FIG. 1;

FIG. 6 is a bottom view of the furniture of FIG. 1;

FIG. 7 is a front perspective view of furniture according to a second embodiment;

FIG. 8 is a front view of the furniture of FIG. 7;

FIG. 9 is a rear view of the furniture of FIG. 7;

FIG. 10 is a right side view of the furniture of FIG. 7, the left side view is a mirror image of the right side view of FIG. 10;

FIG. 11 is a top view of the furniture of FIG. 7;

FIG. 12 is a bottom view of the furniture of FIG. 7;

FIG. 13 is a front perspective view of furniture according to a third embodiment;

FIG. 14 is a front view of the furniture of FIG. 13;

FIG. 15 is a rear view of the furniture of FIG. 13;

FIG. 16 is a right side view of the furniture of FIG. 13, the left side view is a mirror image of the right side view of FIG. 16;

FIG. 17 is a top view of the furniture of FIG. 13; and,

FIG. 18 is a bottom view of the furniture of FIG. 13.

The dashed lines are for purposes of illustrating environmental structure and form no part of the claimed design. The break lines shown in solid lines with adjacent brackets are for purposes of illustrating indeterminate length and form no part of the claimed design.
